INDIANA

WING BRACE ARRANGEMENT FOR RAILROAD SPREADERS

Application filed April 6, 1931. Serial No. 527,873.

This invention relates to improvements in wing brace arrangement for railroad spreaders and it consists of the matters hereinafter described and more particularly pointed out in the appended claims.

In those type of railroad spreaders which include a main spreader wing pivoted for a swinging movement away from and toward the car, into and out of the desired operative position, telescopic braces are employed for holding the wing in the desired angular position. The greatest angular position into which the wing is swung is determined by the length of braces employed and in turn, the length of such braces are limited by other portions such as appliances or the like on the car body and which cannot be removed or changed. With the effective length of the braces thus reduced, it is apparent that the wing cannot be swung into that angular position giving it the greatest spread.

The primary object of our invention is to provide a novel arrangement for the brace whereby the effective length of the brace can be increased to provide greater angularity and operating spread for the wing, without interfering with those appliances recognized as standard upon railway cars and without increasing the overall length of the brace itself in its normal contracted condition as when the wing has been swung in toward the car body.

A further object of the invention is to provide an arrangement of this kind which is simple in construction because of the few parts embodied therein, along with the ease of assembling them and which arrangement is strong and rigid and operates efficiently for its intended purpose in providing that extra length in the brace so desired without resorting to increasing the lengths of the brace parts themselves.

The above mentioned objects of the invention, as well as others, together with the many advantages thereof will more fully appear as we proceed with our specification.

In the drawings:—

Fig. 1 is a view in top plan elevation of 50 the rear right hand corner of a railroad

spreader embodying our improved wing brace arrangement.

Fig. 2 is a detail view in side elevation on an enlarged scale of the improved brace arrangement as when the same is folded in toward the car as is best shown in dotted lines in Fig. 1.

Fig. 3 is a detail transverse vertical sectional view through a part of a railroad spreader embodying our invention as taken on the line 3—3 of Fig. 1.

Fig. 4 is a perspective view of a certain extension link forming a part of our invention.

Referring now in detail to that embodiment of the invention illustrated in the drawings; 1 indicates as a whole a part of the car of a railroad spreader including side sills 2, center sills 3 and cross members 4, 5, 6 and 7 respectively. Associated with the cross member 4 at one side of the car is an upright wing post 8 upon which a wing post carriage 9 is mounted for a vertical guided movement. This carriage includes laterally extending ears 10 to which a hinge plate 11 is pivoted 70 for a swinging movement about a vertically disposed pin 12.

13 indicates the main spreader wing of the car having its inner or front end pivoted to the hinge plate 11 by a horizontal pin 14. 80 The outer or rear end of the main spreader wing has pivoted thereto, an extension or bank shaper wing 15, in the manner well known. By the construction described the main spreader wing along with the extension or bank shaper wing, may be swung away from or toward the car about the pin 12 as an axis and said wing may be swung into the desired vertical angular position about the hinge pin 14 as an axis.

To swing the wing away from the car into the desired operative position, and in toward and parallel with the side of the car as when the car is being transported from one place of use to another, we provide a power cylinder 16 and associated piston rod 17. The inner end of the power cylinder has a universal-like joint connection 18 with the side sill 2 near the cross member 5 while the outer end of the piston rod has a similar joint con-

nection 19 with the inner or rear side of the main spreader wing. Said power cylinder is adapted for operation by means of fluid under pressure and therefore there is connected to each end thereof, conduits 20 and 21 leading from a source of fluid under pressure such as an air tank 22 located on the car. A suitable valve 23 controls the admission and exhaust to said cylinder ends. Thus 10 when such fluid is admitted to the inner end of the cylinder, the piston rod is projected outwardly and this swings the wing away from the car body into the desired operative position. When such fluid is admitted to the outer end of the cylinder, said rod is retracted into the cylinder and the wing is swung inwardly toward the car. In this movement of the wing, the cylinder 16 swings into a position substantially parallel with 15 and above the side sill.

Associated with the wing for holding it into the desired position into which it has been swung by the power cylinder 16 and rod 17, there is provided a plurality of braces 24, 25 and 26 respectively. The braces 24, and 25 are arranged between the car body and wing proper while the brace 26 is arranged between the car body and the extension or bank shaper wing. All braces are of a similar structure in that each includes inner and outer telescopic brace parts 27 and 28 respectively and in each instance there is mounted on the outer end of the inner telescopic member, a power actuated locking device 29 adapted for engagement with a toothed bar 30 on the associated brace member 28.

Each member 27 of the braces 24 and 25 is operatively connected by a two-way or universal-like joint 31 with the car body, while the outer end of each member 28 of all of said braces is operatively connected by a somewhat similar joint 31^a with the rear or inner surface of the wing 13 and its extension 15 as best shown in Fig. 1. This joint 31^a also has a pivotal movement with respect to the member 28 and therefore provides a three way movement instead of a two-way movement as provided by the joint 31. Each locking device 29 is of the pressure fluid kind and therefore each has a conduit 32 connected thereto. All of the conduits which are flexible are connected to a header 33 leading from the tank 22 and in said header is a valve 34 for controlling the passage of such fluid into and out of the various locking devices.

The inner end of the member 27 of the brace 26 is connected to the car in a manner different from the connection of the like member of the braces 24 and 25 with said car. On the outside of the sill member 2, near the cross member 7, is attached a plate 35 having top and bottom vertically spaced ears 36—36 arranged toward the rear end thereof.

65 Near the front end of said plate is provided

a pair of vertically spaced ears 37 spaced a vertical distance apart less than that of the ears 36 and said ears 37 have registering openings 38 therein. On the top of this plate 35 is a horizontal flange 39 upon which is engaged an upright power cylinder 40 including a piston actuated rod or locking pin 41 adapted to be entered through and withdrawn from the openings 38 in the ears 37.

A link 42 is provided at one end with top and bottom pairs of ears 43 to receive the ears 36 of the plate 35 and a pin 44 is inserted through all of said ears whereby the link is capable of a swinging movement from a position substantially parallel with the car body into a position at substantially a right angle thereto as best shown in Fig. 1. The other or outer end of said link is provided with spaced ears 45 between which a knuckle 46 is pivoted at one end by a vertically disposed pivot pin 47. The other end of said knuckle is pivoted to the inner end of the member 27 of the brace 26 by a horizontal pin 48 whereby a two-way or universal-like joint connection is provided between the brace 26 and link 42 and which connection is similar to the joint 31 before mentioned.

On one side of the link 42 is provided an ear 49 having an opening 50 therein. Said ear is so disposed on the link that when said link is in its extended position, as shown in full lines in Fig. 1, it will enter between the ears 37 of the plate 35, so that its opening 50 will register with the openings 38 in said ears 37.

In the operation of the wing brace arrangement shown, let it be assumed that the wing 13 and its extension 15 have been swung in toward the side of the car and are substantially parallel therewith. This provides sufficient clearance for passing trains on adjacent tracks and is the position the wing occupies when the spreader car is in transit.

Under such condition, the various braces are all in their contracted condition as is the cylinder 16 and its rod 17 and all extend substantially parallel with and along-side the car body, the link 42 occupying a folded-in position, also substantially parallel with the car body as shown in dotted lines in Fig. 1. To swing the wing into its operative position, the valve 23 is actuated to admit fluid under pressure into the rear end of the cylinder 16 to project the rod 17 outwardly and this will swing the wing 13 and its extension about the pin 12 away from the side of the car into its fullest extended angular position as shown in Fig. 1. In this swinging movement of the wings, the locking means 29 of each brace is rendered inoperative so that the part 28 of each brace is withdrawn from the part 27 thereof. In this movement of the braces, the brace 26 will pull the link 42 around into the full line extended position shown in Fig. 1, at which time the ear

49 of the link will swing into a position between the ears 37 of the plate 35 wherein the openings 38 and 50 in said ears register. Thereafter the pin or rod 441 of the cylinder 40 is actuated to enter the registering openings to lock the link in this position. It is pointed out that when the brace 26 is in this position, the various pivot connections associated therewith are all in substantially the same plane so that the pressure transmitted to the brace from the extension wing is better resisted without a tendency to buckle either the brace or link. That end of the link to which the brace member 27 is connected is offset laterally as shown to accommodate the rear end of the brace member 27 when the parts are in the position along-side the car.

By reason of the use of the link described, we are enabled to obtain a brace arrangement that is of an effective length greater than the combined length of the two members constituting the brace proper. In this manner, a greater angularity of the wing in its operative position is obtained without unduly increasing the combined length of the wing and its extension. Thus a wider spread is had with the same size wing than it has heretofore been possible. It is apparent that the operative range of the spreader has been increased without making the wing and its extension so long as to project beyond the rear end of the car in transport.

While in describing the invention, we have referred in detail to the form, arrangement and construction of the various parts thereof, the same is to be considered merely as illustrative, so that we do not wish to be limited thereto except as may be specifically set forth in the appended claims.

We claim as our invention:—

1. A spreader embodying therein a car member and a wing member pivoted at one end thereto for a swinging movement into and away from its angular operating position with respect to the car member, a brace comprising a plurality of parts disposed between said car and wing members for holding the wing member in its operative position and means between one end of said brace and one of said members for increasing the effective length of the brace beyond that of the combined length of the parts comprising said brace.

2. A spreader embodying therein a car member and a wing member pivoted at one end thereto for a swinging movement into and away from its angular operating position with respect to the car member, a brace comprising a plurality of parts disposed between said car and wing members for holding the wing member in its operative position and means between one end of the brace and the car member for increasing the effective length of the brace beyond that of the combined

length of the parts constituting said brace.

3. A spreader embodying therein a car member and a wing member pivoted at one end thereto for a swinging movement into and away from its angular operating position with respect to the car member, a brace disposed between said car and wing members for holding the wing in its operative position, said brace comprising a plurality of telescopic parts and means between one of said members and end of one of said telescopic parts for increasing the effective length of the brace beyond that of the combined length of the telescopic parts of the brace.

4. A spreader embodying therein a car member and a wing member pivoted at one end thereto for a swinging movement into and away from its angular operating position with respect to the car member, a brace disposed between said car and wing members for holding the wing in its operative position, said brace comprising a plurality of telescopic parts and means between the car member and one end of one of said telescopic parts for increasing the effective length of the brace beyond that of the combined length of the telescopic parts of the brace.

5. A spreader embodying therein a car member and a wing member pivoted at one end thereto for a swinging movement into and away from its angular operating position with respect to the car member, a brace comprising a plurality of parts disposed between said car and wing members for holding the wing member in its operative position and means pivoted to one of said members and to one end of the brace for increasing the effective length of the brace beyond that of the combined length of the parts constituting the brace.

6. A spreader member embodying therein a car member and a wing member pivoted at one end thereto for a swinging movement into and away from its angular operating position with respect to the car member, a brace comprising a plurality of parts disposed between said car and wing member for holding the wing member in its operative position and means pivoted at one end to the car member and pivoted at its other end to one end of the brace for increasing its effective length beyond that of the combined length of the parts constituting the brace.

7. A spreader member embodying therein a car member and a wing member pivoted thereto for a swinging movement into and away from its angular operating position, a brace comprising a plurality of parts disposed between said car and wing member for holding the wing member in its operative position and means pivoted at one end to one of said members and pivoted at its other end of said brace parts, said means normally extending substantially parallel with one of said members when the wing member is disposed alongside the car member, said means in the swinging

movement of the wing member away from the car member swinging into a position substantially parallel with the brace for increasing its effective length beyond that of the combined length of the brace parts.

8. A spreader member embodying therein a car member and a wing member pivoted thereto for a swinging movement into and away from its angular operating position, a brace comprising a plurality of parts disposed between said car and wing members for holding the wing member in its operative position and means pivoted at one end to the car member and pivoted at its other end to one end of the brace, said means normally extending substantially parallel with the car member when the wing member is disposed alongside thereof, said means in the swinging movement of the wing member away from the car member swinging into a position substantially parallel with the brace and acting as an extension for increasing the effective length of the brace beyond that of the combined length of the parts constituting the brace.

9. In combination with a car member and a wing member pivoted thereto for a swinging movement, a brace member including telescopic parts, one of said parts being pivoted at one end to one of said members and pivoted at its other end to one end of a link in turn pivoted at its other end to said other member for a swinging movement toward and away from the car and means for locking the link in a position extending away from the car.

10. In combination with a car member and a wing member pivoted thereto for a swinging movement, a brace comprising a plurality of telescopic parts, means pivotally connecting one end of said brace to the wing member, a link pivoted at one end to the car member for a swinging movement toward and away from the car, means pivotally connecting the other end of said brace and link together and means for locking the link in a position extending away from the car.

11. In combination with a car member and a wing member pivoted thereto for a swinging movement, a brace comprising a plurality of telescopic parts, means pivotally connecting one end of said brace to the wing member, a link pivoted at one end to the car member and means providing a joint with more than one axis for pivotally connecting the other end of said brace and link together.

12. In combination with a car member and a wing member pivoted thereto for a swinging movement into and out of operative position, means operating upon the wing for imparting a swinging movement thereto, a brace between said car and wing and including telescopic parts, one of said brace parts being pivotally connected at one end to one of said members and means connecting the

other end of said brace with said other member and operating in the swinging movement of the wing away from the car member as an extension for said brace to increase its effective length.

13. In combination with a car member and a wing member pivoted thereto for a swinging movement into and out of operative position, means operating upon the wing for imparting a swinging movement thereto, a brace between said car and wing and including telescopic parts, one of said brace parts being pivotally connected at one end to the wing member and means pivotally connected to the other end of the brace and to the car member respectively and operating on the swinging movement of the wing away from the car body as an extension for the brace to increase its effective length.

14. In combination with a car member and a wing member pivoted thereto for a swinging movement, a brace member pivotally connected at one end to one of said members, a link, means pivotally connecting the other end of said brace member to one end of said link, means pivotally connecting the other end of said link to the other of said members and acting as one extension for the brace when the wing has been swung into a position away from the car and means for locking said link to its associated member against movement when acting as an extension of the brace.

15. In combination with a car member and a wing member pivoted thereto for a swinging movement, a brace member connected at one end to the wing, a link, means pivotally connecting one end of the link to the other end of the brace, means pivotally connecting the other end of the link to the car member and acting as an extension for the brace when the wing has been swung into a position away from the car and means for locking said link to the car member against movement when acting as an extension of the brace.

16. In a railroad spreader, a car, a wing pivoted thereto, a brace, means for pivotally connecting one end of the brace with the wing, a plate on the car, a link pivoted at one end to said plate and pivoted at its other end to the other end of the brace and which link acts as an extension for the brace when the wing has been swung away from the car and means for connecting the plate and link to hold the link against movement when acting as an extension for said brace.

17. In a railroad spreader, a car, a wing pivoted thereto, a brace, means for pivotally connecting one end of the brace with the wing, a plate on the car, a link pivoted at one end to said plate and pivoted at its other end to the other end of the brace and which link acts as an extension for the brace when the wing has been swung away from the car,

5 a projection on said plate, an ear on said link adapted to engage the projection on the plate when said link acts as an extension for the brace and means for connecting said projection and ear together for locking the link in said position forming an extension for the brace.

10 18. In combination with a railroad spreader embodying therein a car member, a wing member pivoted thereto for a swinging movement away from and toward the car, means for imparting such movement to said wing member, a plurality of extensible braces between the wing and car members for holding the wing member in a position away from the car member and a link between one of said braces and one of said members and operating as an extension for said brace when said wing is in its position away from said car.

15 19. In combination with a railroad spreader embodying therein a car member, a wing member pivoted thereto for a swinging movement away from and toward the car, means for imparting such movement to said wing member, a plurality of extensible braces between the wing and car members for holding the wing member in a position away from the car member and a link pivotally connected at one end to one of said members and at its other end to said car member and operating as the wing swings into its position away from the car, to provide an extension for said brace.
